UNITED STATES PATENT OFFICE.

VERNON GARNER, OF BOSTON, MASSACHUSETTS, ASSIGNOR TO UNITED PRINTING MACHINERY COMPANY, OF BOSTON, MASSACHUSETTS, A CORPORATION OF MAINE.

SHEET-FEEDING MACHINE.

1,149,574.

Specification of Letters Patent. Patented Aug. 10, 1915.

Application filed June 2, 1914. Serial No. 842,339.

To all whom it may concern:

Be it known that I, VERNON GARNER, a citizen of the United States, and a resident of the city of Boston, in the county of Suffolk and State of Massachusetts, have invented certain new and useful Improvements in Sheet-Feeding Machines, of which the following is a specification, reference being made to the accompanying drawings, which form a part thereof.

My invention relates to sheet-feeding machines in which successive sheets are separated from a bank, or pile, of sheets, and are then automatically carried forward and presented, one at a time, to a printing press, or other machine, which is to operate on such sheets.

The object of my present invention, among other things, is to provide simple and efficient mechanisms whereby the pile, or bank, of sheets shall be fed forward a slight distance with every stroke, or cycle, of the combing devices, no matter whether the length of time the combers act, or the combing interval, be short or within certain constant limits, but further that the forward feed of the bank of sheets should be increased whenever the combers act for a period exceeding a certain predetermined amount. Therefore, according to my improved device, there will be a slight forward feed of the bank of sheets, with every completed cycle of the combing devices, which forward feed will be increased whenever the length of the comb exceeds a predetermined amount.

In the accompanying drawings this improved bank feed mechanism is shown incorporated in a sheet-feeding machine such as I have shown and described in my application for patent, filed April 7, 1914, Serial Number 830,139, but it will be understood that my improvement may be embodied in various forms of sheet-feeding machines.

Referring to the drawings, Figure 1 shows a side elevation of my improved mechanism, certain non-essential parts being omitted; Fig. 2 shows a side view of my mechanism when the length of the comb ex-

ceeds a predetermined amount; and Fig. 3 shows a view, similar to Fig. 2, when the length of the comb is normal or less than the predetermined amount.

Referring to figures, 1 is the upper loading board, or feed table, of my machine, which table may be supported in the frame 2 as shown in this figure; the upper feed belts 3 travel over pulleys 4 and 5, and extend over the upper surface of the table 1, and around the drum 6 to gradually feed forward the pile, or bank, of sheets resting on the upper table.

7 is the lower loading board, or feed table, attached to the frame 2, and 8 are the lower feed belts passing over the pulleys 9 and 10 journaled in the frame 2, said belts 8 extending over the upper surface of the table 7 to advance the bank of sheets to the combing devices. The drum 6 is secured to the shaft 11 and is rotatable therewith within the frame 2; 12 are a series of curved guides forming a curved throat in conjunction with the periphery of the drum 6. This curved throat leads from the upper feed table 1 to the lower feed table 7, and the bank of sheets, in passing through this throat, is reversed in position. The guides 12 are supported upon the transverse rods 13 and 14. Hollow brackets 15 and 16 are secured at either end of the rods 13 and 14 respectively, and the frame 2 has similar brackets 17 and 18. Coil springs 19 and 20 are secured to the ends of the rods 13 and 14 respectively and also to the frame 2. These springs are of greater tension than the normal pressure brought to bear on the guides 12 by the forward movement and reversing of the bank of sheets.

21 are pressure rollers supported in the frame 2, and are located at the opening of the throat, in order not only to press the bank of sheets against the drum 6, but also direct them into the throat. The drum shaft 11 has secured to it the gear 22, which through a series of pinions 23 and 24, connects with the gear 25 which carries a sprocket wheel 26 over which travels the sprocket chain 27. This sprocket chain 27

- engages with the sprocket wheel 28 toward the forward part of the machine which is carried on the shaft 29 journaled in the frame 2, which shaft 29 also has affixed to it the pulleys 10 over which the lower feed belts 8 pass to advance the bank of sheets.
- 30 is a ratchet secured to the shaft 29 and cooperates with the pawl 31 attached to the rock lever 32 loosely mounted on the shaft 29. The coil spring 33 secured to the rock lever 32 and the frame 2 serves to normally retract the lever 32 with the pawl 31, over the ratchet 30.
- 34 is a link connecting the end of the lever 32 with the lower end of the bell-crank lever 35 journaled in the stay-shaft 36; the upper end of the lever 35 carries the cam roller 37 adapted to coöperate with the cam 38 secured to the actuating cam shaft 39.
- 40 is a stop lug on the link 34, and 41 is a latch lever pivoted on the bracket 42 at 43. The forward end 44 of the lever 41 is adapted to engage with the lug 40, while the rear end 45 carries a cam roller 46 adapted to co-operate with the cam 47 secured to the ratchet segment of the swinging arm 48 which swings in unison with the combing wheel mechanism hereinafter to be described. The coil spring 49 normally pulls the end 30 45 so that the lever 41 is in the position shown in Fig. 3, which downward movement is limited by having the forward end 44 contact with the under surface of the link 34. When the combing devices are short in their 35 operation, or below a predetermined amount, the lateral movement of the link 34 through the lever 35 and cam 38 is limited to the space shown in Fig. 3 between the lug 40 and the end 44 of the lever 41 because the 40 roller 46 is not raised by the cam 47, and the pawl 31 may drop back only one tooth in the ratchet 30; the subsequent forward movement of the pawl 31 through the lever 32, link 34, bell-crank lever 35 and roller 37 45 on the cam 38 rotates the shaft 29 with the sprocket 28 and pulley 10 to advance the bank of sheets a slight distance over the feed table by the mechanism heretofore described. However, when the combing time 50 exceeds the predetermined amount and is long enough so as to increase the swing of the arm 48 sufficiently to allow the cam 47 to engage with the roller 46 as shown in Fig. 2, the latch lever 41 is rocked on the pivot 43, which depresses the end 44 so that the lateral backward movement of the link 34 is increased in proportion with the length of the forward swinging movement of the arm 48 and the lug 40 passes beyond the end 44 55 and the pawl 31 on the lever 32 drops back several teeth on the ratchet 30; the subsequent forward movement of the pawl 31, through the lever 32, link 34, bell-crank lever 35 and roller 37 on the cam 38 rotates the shaft 29 with the sprocket 28 and pulley 10 to advance the bank of sheets a greater distance proportioned to the number of teeth on the ratchet over which the pawl 31 passes in its backward movement.
- 49 is a rock lever connected with the trip mechanism, controlled by the edge of the advancing sheet, which is pivoted to the bracket 42 at 43.
- 50 is a stop pawl integral with 49 adapted to engage the ratcheted teeth in the swing- 75 ing segment of the arm 48.
- 51 is a pressure spring coiled about the rod 52 affixed to the pawl 50 and passing loosely through the bracket 53 secured to the shaft 54 as shown in Figs. 2 and 3. 80
- The construction and operation of the trip mechanism need not be described in order to understand my invention.
- Referring to Fig. 1, 55 is a constantly rotating power shaft attached to any suitable 85 source of power. 56, 57 and 58 are gear wheels, the latter being secured to the shaft 59 which operates the swinging arm 48 through a rock tube journaled about said shaft 59. 60 and 61 are similar gear wheels, 90 the latter being secured to the cam actuating shaft 38 as shown; 62 is one of the combing wheels mounted on the shaft 63 which is constantly rotating through the sprocket chains 64 and 65, the chain 65 receiving its 95 rotation from the shaft 59. This construction enables me to advance the bank of sheets a slight distance with each stroke, or cycle, of the combing devices when the length of the comb is short or below a predetermined amount, which distance for the advance of the bank of sheets is increased whenever the length of the comb exceeds a predetermined amount, the entire forward movement being controlled by the length of 100 the forward swing of the ratcheted arm 48, swinging in unison with the combing wheels. 105
- It is obvious that the advance of the bank in both instances does not occur until after the swinging arm 48, which controls the extent of motion of the bar 34, has permitted the pawl 31 to drop back over the teeth of the ratchet 30.
- I claim as my invention:—
1. In a sheet feeder, the combination with 115 means for operating a combing device, of means for feeding a bank of sheets to the combing device, and means for operating said feed mechanism, when the combing device is out of action, a slight distance with each cycle of the combing device and a greater distance whenever the length of the comb exceeds a predetermined amount.
  2. In a sheet feeder, the combination with 120 means for operating a combing wheel, of means for feeding a bank of sheets to the combing wheel, and means for operating said feed mechanism, when the combing wheel is out of action, a slight distance with each cycle of the combing wheel and a 125
  3. In a sheet feeder, the combination with 130

greater distance whenever the length of the comb exceeds a predetermined amount.

3. In a sheet feeder, the combination with means for operating a combing wheel, of means for feeding a bank of feathered sheets to the combing wheel, and means for operating said feed mechanism, when the combing wheel is out of action, a slight distance with each cycle of the combing wheel and a greater distance whenever the length of the comb exceeds a predetermined amount.

4. In a sheet feeder, the combination with an upper feed table, of a lower feed table, a curved throat between said tables, feed belts for advancing a bank of sheets through said throat, a combing wheel above the lower feed table, and means for operating said feed belts, when the combing wheel is out of action, a slight distance with each cycle of the combing wheel and a greater distance whenever the length of the comb exceeds a predetermined amount.

5. In a sheet feeder, the combination with means for operating a combing device, of means for feeding a bank of sheets to the combing device comprising a ratchet and co-operating pawl, and means for operating said feed mechanism, when the combing device is out of action, a slight distance with each cycle of the combing device and a greater distance whenever the length of the comb exceeds a predetermined amount.

6. In a sheet feeder, the combination with means for operating a combing wheel, of means for feeding a bank of sheets to the combing wheel comprising a ratchet and co-operating pawl, and means for operating said feed mechanism, when the combing wheel is out of action, a slight distance with each cycle of the combing wheel and a greater distance whenever the length of the comb exceeds a predetermined amount.

7. In a sheet feeder, the combination with means for operating a combing wheel, of means for feeding a bank of feathered sheets to the combing wheel comprising a ratchet and co-operating pawl, and means for operating said feed mechanism, when the combing wheel is out of action, a slight distance with each cycle of the combing wheel and a greater distance whenever the length of the comb exceeds a predetermined amount.

8. In a sheet feeder, the combination with means for operating a combing device, of means for throwing said device into action, means controlled by the sheet for throwing said device out of action, means for feeding a bank of sheets to the combing device, and means for operating said feed mechanism, when the combing device is out of action, a slight distance with each cycle of the combing device and a greater distance whenever the length of the comb exceeds a predetermined amount.

9. In a sheet feeder, the combination with

means for operating a combing wheel, of means for throwing said wheel out of action, means controlled by the sheet for throwing the said wheel out of action, means for feeding a bank of sheets to the combing wheel, and means for operating said feed mechanism, when the combing wheel is out of action, a slight distance with each cycle of the combing wheel and a greater distance whenever the length of the comb exceeds a predetermined amount.

10. In a sheet feeder, the combination with means for operating a combing wheel, of means for throwing said wheel out of action, means for feeding a bank of feathered sheets to the combing wheel, and means for operating said feed mechanism, when the combing wheel is out of action, a slight distance with each cycle of the combing wheel and a greater distance whenever the length of the comb exceeds a predetermined amount.

11. In a sheet feeder, the combination with an upper feed table, a lower feed table, a curved throat between said tables, feed belts for advancing a bank of sheets through said throat, a combing wheel above the lower feed table, means for throwing said wheel into action, means controlled by the sheet for throwing said wheel out of action, and means for operating said feed belts, when the combing wheel is out of action, a slight distance with each cycle of the combing wheel and a greater distance whenever the length of the comb exceeds a predetermined amount.

12. In a sheet feeder, the combination with an upper feed table, of a lower feed table, a curved throat between said tables, feed belts for advancing a bank of sheets through said throat operated by a ratchet and co-operating pawl, a combing wheel above the lower feed table, means for throwing said wheel into action, means controlled by the sheet for throwing said wheel out of action, and means for operating said pawl over said ratchet, when the combing wheel is out of action, a single tooth with each cycle of the combing device and a plurality of teeth whenever the length of the comb exceeds a predetermined amount.

13. In a sheet feeder, the combination with means for operating a combing device, of means for feeding a bank of sheets to the combing device comprising a ratchet and co-operating pawl, and means for operating said pawl over said ratchet, when the combing device is out of action, a single tooth with each cycle of the combing device and a plurality of teeth whenever the length of the comb exceeds a predetermined amount.

14. In a sheet feeder, the combination with means for operating a combing device, of means for throwing said device into action, means controlled by the sheet for

throwing said device out of action, means for feeding a bank of sheets to the combing device comprising a ratchet and cooperating pawl, and means for operating said pawl over said ratchet, when the combing device is out of action, a single tooth with each cycle of the combing device and a plurality

of teeth whenever the length of the comb exceeds a predetermined amount.

VERNON GARNER.
